(57) **CLAIM**

The ornamental design for a heel pattern for shoe, as shown and described.

DESCRIPTION

FIG. 1 is a perspective view of an embodiment of a heel pattern for a shoe;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken line portions shown in FIGS. 1-7 are for illustrative purposes only and form no part of the claimed design. FIGS. 1 to 7 include textured portions, which is design to show a stitched fabric of the embodiment's design.
